US00D943267S

(12) **United States Design Patent** (10) **Patent No.:** **US D943,267 S**
(45) **Date of Patent:** **** Feb. 15, 2022**

(54) **PILL BOX**

(71) Applicant: **Guangzhou Ruidu Electronic Technology Co., Ltd.**, Guangzhou (CN)

(72) Inventor: **Ruiming Cen**, Guangzhou (CN)

(73) Assignee: **Guangzhou Ruidu Electronic Technology Co., Ltd.**, Guangzhou (CN)

(**) Term: **15 Years**

(21) Appl. No.: **29/779,525**

(22) Filed: **Apr. 20, 2021**

(51) LOC (13) Cl. **03-01**

(52) U.S. Cl.

USPC **D3/203.3**

(58) **Field of Classification Search**

(57) **CLAIM**

The ornamental design for a pill box, as shown and described.

DESCRIPTION

FIG. 1 is a perspective view of a pill box, showing my new design;

FIG. 2 is a top plan view thereof;

FIG. 3 is bottom plan view thereof;

FIG. 4 is a front elevation view thereof, the rear elevation view being the same;

FIG. 5 is a left side elevation view thereof, the right side elevation view being the same;

FIG. 6 is a perspective view of the pill box, shown in an alternative configuration for clarity of illustration;

FIG. 7 is top plan view of FIG. 6; and,

FIG. 8 is bottom perspective view of FIG. 6.

1 Claim, 8 Drawing Sheets
